UNITED STATES PATENT OFFICE.

SOPHIA STEELMAN, OF SOMERS POINT, NEW JERSEY, ASSIGNOR OF ONE-HALF TO WILLIAM A. BARRITT, OF SAME PLACE.

WASHING-MACHINE.

SPECIFICATION forming part of Letters Patent No. 290,134, dated December 11, 1883.

Application filed June 30, 1882. Renewed August 28, 1883. (No model.)

To all whom it may concern:

Be it known that I, SOPHIA STEELMAN, of Somers Point, in the county of Atlantic and State of New Jersey, have invented certain new and useful Improvements in Washing-Machines; and I do hereby declare that the following is a full, clear, and exact description of the invention, which will enable others skilled in the art to which it appertains to make and use the same, reference being had to the accompanying drawings, which form a part of this specification.

Figure 1 is a vertical longitudinal sectional view of my improved washing-machine. Fig. 2 is a detail view of the "carrier" attachment to the pounders. Fig. 3 is a plan view of one of the pounders.

Corresponding parts in the several figures are denoted by like letters of reference.

This invention relates to washing-machines; and it consists in certain improvements in the construction of the same, which will be hereinafter fully described, and particularly pointed out in the claim.

In the drawings hereto annexed, A represents the suds-box, which is rectangular in shape and supported upon legs B. Box A has a central partition, C, over which is arranged a cross bar or brace, D, supporting the operating mechanism, to be hereinafter described. The compartments E E of box A each contain a smaller box, F, supported upon legs G, and having perforated bottom and sides, as at H. Suitable covers, G', are provided to close the said boxes F and the compartments E. The cross bar or brace D supports an upright, I, to which is pivoted a lever, J, having at its ends hinged rods or staffs K, projecting downward through suitable openings in the covers G, and carrying at their lower ends the pound-

ers or dashers L, which move vertically in the boxes F. The said pounders consist of plates or disks having perforations M, through which water may pass on the downstroke. The lever J is provided at one end with a handle, N; by 45 which it may be conveniently operated.

O represents a frame, made of wire, and provided at one end with hooks P P and at the other end with eyes Q Q. Said frame is also provided with transverse cross-bars R. One 50 of these frames may be adjusted upon each of the pounders, which are provided with eyes S and studs T, to engage the hooks and eyes P Q, as shown. When large or heavy articles of clothing are to be washed, they may be hung 55 upon the cross-bars R of these frames, and thus be carried through the water at each stroke of the pounder.

From the foregoing description, taken in connection with the drawings hereto annexed, 60 the operation of my invention will be readily understood. By dividing the clothes between the two compartments, each stroke is made to tell, and time is thus saved without extra expenditure of power. Fine and coarse articles 65 may thus be also conveniently separated.

The machine is simple and inexpensive and easily operated.

I claim and desire to secure by Letters Patent of the United States—

The combination, with the pounders having eyes S and studs T, of the frames O, having hooks P, eyes Q, and cross-bars R, as set forth.

In testimony that I claim the foregoing as my own I have hereto affixed my signature in 75 presence of two witnesses.

SOPHIA STEELMAN.

Witnesses:

THOS. E. MORRIS,

SARAH B. BARRETT.
